Attest:

UNITED STATES PATENT OFFICE

CONRAID EURICH, OF PITTSBURG, ASSIGNOR OF ONE-HALF TO JOHN EURICH, OF ALLEGHENY COUNTY, PENNSYLVANIA.

PRESSURE-REGULATOR.

SPECIFICATION forming part of Letters Patent No. 389,065, dated September 4, 1883.

Application filed January 14, 1883. Serial No. 260,780. (No model.)

To all whom it may concern:

Be it known that I, CONRAID EURICH, a citizen of the United States, residing at Pittsburg, in the county of Allegheny and State of Pennsylvania, have invented certain new and useful Improvements in Pressure-Regulators; and I do hereby declare the following to be a full, clear, and exact description of the invention, such as will enable others skilled in the art to 10 which it pertains to make and use the same, reference being had to the accompanying drawings, which form a part of this specification.

My invention relates to an improvement in pressure-regulators, the object being to close 15 the valve against the diaphragm, and thereby avoid any quick movement of the same and prevent "knocking." This I accomplish by certain details of construction and combination of parts, as will be fully set forth herein- 20 after.

In the accompanying drawings, Figure 1 is a sectional elevation of my improved pressure-regulator constructed in accordance with my invention. Fig. 2 is a sectional plan view of 25 the same, taken on the line *x x*.

To put my invention into practice, I provide a cylindricel box, *a*, divided by partitions into a number of compartments, the largest of which, *b*, is covered with a cap, *c*, and securely attached to the box *a* by a number of bolts, *d*. Through the center of this box *a* is a vertical valve-rod, *e*, having rigidly attached thereto two valves, *f*, each having a seat formed in the partitions *g*, which divide the lower 35 portion of the box *a* into three compartments, *h i*. These two valves *f* are made of different sizes, so that the area or surface of the valves against which the gas presses is different, the lower valve being smaller than the upper to 40 permit the gas under high pressure to elevate the valves and rod. Attached to two of these chambers *h i* is the inlet-pipe *k* and outlet *l*, the first-mentioned pipe, *k*, carrying a high pressure of gas or other substance, and 45 the other, by means of the working of the valve *f*, a low or moderate pressure.

Between the top chamber, *b*, and that, *h*, beneath is a valve-seat formed in the dividing-wall *m* between the two chambers *b h*, in 50 which seat a loose valve, *n*, is made to operate. The loose sliding valve *n* is normally elevated off its seat when the valves *f* are closed by

means of a system of levers, *p p'*, connected to said valve and the vertically-movable valve-rod *e*. The upper lever, *p*, is fulcrumed at an intermediate point of its length to an upright arm, *w*, of a fixture, *w*, secured to the dividing-wall *m* of the upper large chamber, *b*, in which chamber the system of levers is located, and one end of said lever has a slotted connection 6c with the valve-rod *e*, as at *p*, while the other end thereof is connected to the lower lever, *p'*, by an intermediate link, *p*. This lower lever is fulcrumed at one end to the fixture *w*, and has a slotted connection at an intermediate 65 point of its length with sliding valve *n*, as at *p*. (Clearly shown in Fig.1.) The sliding valve *n* moves in a reverse direction to the valves *f* and rod *e*, being seated when the latter are elevated by the system of levers depressing 70 the same, and this movement of the levers and valve is assisted by means of coiled springs *o*. Through the valve *n* is formed a transverse opening, *q*, to allow the gas to escape slowly 75 from the larger chamber, *b*, to the next largest chamber, *h*, beneath the same, with which chamber *h* communicates the low-pressure pipe *l*.

Between the top flange of the upper chamber, *b*, and the cap *c* is a flexible diaphragm, *r*, secured rigidly to its center to the valve-stem *e* by means of suitably-constructed washers *s*. Several weights, *t*, placed on the top of the valve-stem *e*, serve as a means for regulating the opening and closing of the valve *f*. 85

In operation the gas under high pressure elevates the different-sized valves *f* and rod *e* a sufficient distance off the seats to permit the gas to enter the chambers *h* and *b*, the valve *n* being opened and the levers *p p'* and valve 90 being unaffected by this initial movement of the valves *f* and rod *e* by reason of the slotted connections between the rod *e*, valve *n*, and levers *p p'*. The gas entering the chamber *b* acts against the diaphragm therein to wholly 95 elevate the valve-rod *e* and valves *f*, and on the further upward movement of the valve-rod the levers *p p'* are depressed to force the valve to its seat, and thus cause the gas to escape from the chamber *b* through the ports *q* 100 into the chamber *h* and low-pressure pipe, thus obviating the quick or rapid return of the valves *f* to their seats.

Having thus described my invention, what I

claim, and desire to secure by Letters Patent, is—

1. In a pressure-regulator such as described, the combination consisting of valve-stem *e*, operated vertically by means of a diaphragm, *r*, the valves *f*, operated by the pressure of gas entering the chamber *i*, and a loose valve, *n*, secured to the stem *e*, so governed by a system of levers, *p*, as to move in an opposite direction to the valve-stem *e*, substantially as set forth.
2. In combination with a diaphragm pressure-regulator, the valve *n*, loosely attached to

the stem *e*, the springs *o*, one or more openings, *q*, through the said valve *n*, and connections between the valve-rod *e* and the valve *n* for operating the same, substantially as described. 15

In testimony that I claim the foregoing I hereunto affix my signature this 6th day of 20 January, A. D. 1888.

CONRAID EURICH. [L. S.]

In presence of—

C. C. LEE,
M. E. HARRISON.
